UNITED STATES PATENT OFFICE

141,218

DESIGN FOR A MONUMENT

Maura Norcross, Manville, R. I.

Application November 20, 1944, Serial No. 116,457

Term of patent 14 years

(Cl. D79—2)

To all whom it may concern:

Be it known that I, Maura Norcross, a citizen of the United States of America, residing at Manville, county of Providence, State of Rhode Island, have invented a new, original, and ornamental Design for a Monument, of which the following is a specification, reference being had to the accompanying drawing, forming a part thereof.

Fig. 1 is a front elevational view of a monument showing my new design; and

Fig. 2 is a side elevational view thereof.
The dominant and characteristic features of the design are shown in full lines in the drawing.

I claim:

The ornamental design for a monument, substantially as shown and described.

MAURA NORCROSS.
